(57) **CLAIM**

The ornamental design for a portable fluorescent light, as shown and described.

DESCRIPTION

FIG. 1 is a perspective view of a portable fluorescent light showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view showing the state where a light transmissive portion has been pivoted.

The shading on the cover on the front side of the fluorescent tubes in FIGS. 1, 4 and 8 illustrates transparency.
